UNITED STATES PATENT OFFICE.

JOHN CASEY AND MURRAY S. CHISM, OF PHILADELPHIA, PENNSYLVANIA.

SPECTACLE OR EYEGLASS CASE.

SPECIFICATION forming part of Letters Patent No. 602,825, dated April 26, 1898.

Application filed June 29, 1896. Serial No. 597,815. (No model.)

To all whom it may concern:

Be it known that we, JOHN CASEY and MURRAY S. CHISM, citizens of the United States, residing in the city and county of Philadelphia, State of Pennsylvania, have invented a new and useful Improvement in Spectacle or Eyeglass Cases, which improvement is fully set forth in the following specification and accompanying drawings.

Our invention consists of a spectacle or eyeglass case formed of a bulging body, a mouth having walls with diverging sides, and a lid hinged to said body, the sides of said lid converging from the outer end of the same to the hinge of said lid, so as to provide increased room for the insertion of the lens and a wide passage when the lid is opened, while said hinge is narrow and straight.

Figure 1 represents a front or face view of a case embodying our invention. Fig. 2 represents a side elevation thereof. Fig. 3 represents a transverse section thereof on line $x x$, Fig. 1.

Similar letters of reference indicate corresponding parts in the several figures.

Referring to the drawings, A designates the body of the case, the same consisting of the front B and the curved back C, said front being bulging in longitudinal direction and having parallel sides D and the rounded bottom E, said front tapering toward said bottom at its end portion E', as most plainly seen in Fig. 2. The upper portion of the body is occupied by a lid or top F, which has tapering sides G and the rounded upper end H, said end conforming to the upper end C' of the back C, said ends having fastenings C² thereon. The face of said top is tapering or receding from its inner termination to said top

H, it being noticed that said top is connected with the front B by means of the hinge J, one butt K of which consists of a wide piece of metal, which extends to the back of the casing and which is riveted or otherwise firmly connected with the adjacent portion of the front B. Projecting from the front at the sides G of the top F are the walls L, which are above the ends of said butt K and are continuities of the upper portion of said front 50 and have their inner sides flaring, so as to accord with the tapering sides G of the top F.

It will be seen that when the top F is open it affords a large space for the entrance and

removal of spectacles or an eyeglass and that a narrow hinge is provided for said lid, the 55 ends of which are inclosed by the walls L, so as to remove said ends from contact with the pocket, while said walls strengthen the portion of the body A around the joints formed by the top F and the portion of the body B at 60 said hinge, which latter, being uncovered when the top is opened, is reinforced or strengthened by the leaf or butt K, which extends across the face of the body and is rigidly connected therewith, as has been stated. 65 It will also be seen that the lid is bulging, so as to provide ample room for the insertion of the lens within the same, and its outer end entirely covers the adjacent end of the back, 70 it being of the full width of said end or approximately so. The sides of said lid converge from said outer end to the hinge J, which is accordingly narrow and made straight or right lined, while the general bulge of the body and lid is preserved. The walls L of 75 the mouth of said body aside of said lid are also bulged or rounded and have their inner edges diverging and closed by the converging sides of the lid. Furthermore, the shape of the body of the case is such that, owing to its 80 curved back and bulging front, it possesses the greatest holding capacity, while the general contour of the case is such that it occupies a minimum space in the pocket.

We are aware that it is not new to hinge 85 the lower end of the lid to the side of a case and have the lid close at the end thereof; but we are not aware that it is common to form the lid with a narrow lower end and flaring sides widening toward the top, whereby a portion of the front of the casing aside of the lid 90 is integral with the back thereof, so that the upper portion of the case is strengthened.

Having thus described our invention, what we claim as new, and desire to secure by Letters Patent, is—

A case consisting of a bulging body, a mouth having walls with diverging edges, and a lid hinged to said body, the sides of said lid converging from the outer edge of the same to 100 the hinge of said lid, said hinge being straight.

JOHN CASEY.
MURRAY S. CHISM.
